HANS GREGGERSEN, OF HAMBURG, GERMANY

AUTOCOGENOUS CUTTING APPARATUS

Application filed April 20, 1929, Serial No. 259,275, and in Germany June 5, 1928.

This invention relates to an apparatus for the autogenous cutting of holes in metal.

A primary object of the present invention is the provision of means whereby the apparatus as a whole may be readily and conveniently secured to the surface on which it is working through the use of the well understood suction principle to thereby permit the device to be used against vertical or inclined walls.

A further object of the invention is the provision of valves for the control of the cutting process, together with means by which the valves are set by hand but in which the succession of their operation is automatically determined.

A further object is the provision of means whereby the ratio of movement of the burners with respect to the manual control may be readily set and maintained throughout the operation.

The invention is illustrated in the accompanying drawings, in which:

Figure 1 is a view in side elevation of the improved apparatus.

Figure 2 is a plan of the same.

Figure 3 is a transverse section through the base plate.

Figure 4 is a plan of a pedal, showing the means for controlling the proportion of movement of the burners with respect to the manually operable element.

The apparatus includes a base plate i of hollow form, the bearing edge of which is provided with a sealing gasket i_1 , preferably a rubber ring. A diaphragm i_3 having a diameter substantially corresponding to the interior of the base is secured at its peripheral edge to the inner side of the top of the base and is connected at its central portion to a bar α having teeth to cooperate with a pinion n supported upon a shaft n_1 extending transversely of the base and operable by a handle h . By suitable operation of the handle, the diaphragm may be moved within the base to reduce or increase the area thereof open to the suction.

The interior of the base is open to a suc-

tion effect through a channel y , and with the diaphragm depressed, as indicated in Figure 3, it will be apparent that the base, under a substantial rarefaction of the air therein, will be secured to any surface with which the sealing gasket i_1 may properly engage. Furthermore, after rarefaction of the air within the base, the holding effect may be materially increased by operating the shaft n_1 to raise the diaphragm i_3 , as will be obvious.

Supported on a plate carried above or beyond the base by suitable pedestals are spaced valve chambers, one of which has a nipple extension k_4 by which it may be connected to a suitable source of supply of oxygen, and the other of which has a nipple i_6 through which the valve casing may be connected to a suitable source of supply of gas for the preheating jet. The valve chamber in communication with the oxygen nipple k_4 is provided with independent valves k , k_1 , k_2 and k_3 , while the valve chamber in communication with the gas nipple i_6 is provided with independent valves i_4 , i_7 and i_8 . Between the valve chambers is arranged a rotating cylinder-like body adapted for rotation through a hand wheel l_2 , on which body is arranged a series of cams l_1 adapted, in the rotation of the body, to actuate levers m_1 connected in any appropriate manner with the respective valves, so that on rotation of the body the valves are automatically actuated in the proper sequence for the desired results.

An injector i_6 is in communication with an oxygen valve k , this injector being in communication by a pipe i_5 with a gas valve i_4 and through the latter by a conduit g' with the suction conduit y of the base, said suction conduit y being in communication with a vacuum meter r by a pipe i_2 in order that the degree of vacuum may be determined. The oxygen admitted by the opening of the valve k through the injector passes beyond the latter through an outlet conduit o and may serve for cooling the burners if necessary.

- Rising from the base is a hollow pedestal in which is rotatably supported a standard *a*. On the standard is rotatably supported a pantograph construction *d* at one apex of 5 which is arranged a vertical pipe carrying at its lower end a nozzle *b* which is appropriately formed to provide a cutting jet. The pipe leading to this jet *b* is in communication with the oxygen valve *k*₃.
- 10 Carried by the pantograph in slightly offset relation from the cutting jet is a pipe terminating in a nozzle formed as a pre-heating jet *c*, and this preheating jet is in communication with the oxygen valve *k*₂ 15 and also in communication with the gas valve *i*₇. The operative end of the pantograph is arranged as a bolt *e* designed to be operated by hand for shifting the respective jets in accordance with the operation 20 of the bolt. The jet-carried end of the pantograph is shifted to selectively position either jet for operation through the medium of a bar *x*¹ connected to the pivot of the pantograph and movable over a sector-shaped plate *x*² secured to the standard *a*. The end of the bar *x*¹ remote from the shaft or standard *a* is provided with a gear *g* co-operating with teeth on the curved edge of the sector *x*² so that the bar may be temporarily held in adjusted position. Obviously, through shifting the bar throughout its range of movement, the jets will be shifted, so that a particular jet may occupy a predetermined position.
- 30 The bolt *e* is provided with a hollow extension in which is slidably a graduated rod *e*₁, one end of such rod being fastened to the bar *x*¹. By adjusting the bolt through the medium of this bar, it will be apparent that the radius of movement of the jet end of the pantograph may be readily governed, it being understood that the connection between the bar *e*₁ and the bar *x*¹ provides a center *e*₂ about which the bolt 40 is moved as a crank in controlling the movement of the jets.
- The base *i* is provided with a bar pivotally connected thereto and terminating in a centering point *f*, which latter is designed 45 to be moved downwardly into cooperation with a punch hole *f*₁ formed in the material for indicating the position of the contemplated hole.
- 50 As soon as the point of the centering apparatus *f* reaches into the punch mark *f*₁, the apparatus is set upon the center of the hole. By means of a gear wheel *g* and a gear segment *x*³, first the cutting burner is set upon the center of the hole or 10 mm. 55 from the periphery, and after the cutting through the ring burner is set likewise, thereby insuring that the flattened side of the gear wheel *g* (Figure 4) must lie against the segment *h*. In the setting of 60 Figure 4 the cutting-through burner *b*

stands upon the center of the hole. Upon shifting the gear wheel *g* into the dot-and-dash line position, the cutting burner *c* is set upon the center of the hole. By releasing the lever *e*₁ a templet lying below the same may be traversed by the bolt *e* in a suitable manner, so that the burners *b* and *c* will correspondingly execute the same motion.

65 The valves *k*, *k*₁, *k*₂, *k*₃ and *i*₇, *i*₄, *i*₈ may now be operated in any desired way. It has already been noted that the valve *k* is connected with the injector *i*₆. The valve *k*₂ must, on the other hand, serve as the admission for the oxygen in the preheating jet *c*, and the valve *k*₃ as oxygen admission valve for the cutting jet *b*. On the contrary, the valve *i*₄ has already been connected as air passing valve to the injector *i*₆. The valve *i*₇ must serve as gas inlet valve for the preheating jet. Of course, other valves for specified purposes may also be present. Thus, for example, in the exemplary embodiment the valve *i*₈ is intended for the purpose of discharging, when lifted, a gas stream over a conduit *k*₄ in the centering apparatus, from the point of which the gas stream is discharged. By setting the centering apparatus against a thin incandescent wire, this gas flame may be ignited and then be used for igniting the preheating flame. A suitable induction ignition may also be provided.

70 Further, an element which controls the circular cut may also be affected by the operating shaft *l*; for example, a clock-work may be mechanically connected into or out of service or a suitable motor may be influenced by the shaft. This automatic operation of the jets in contrast to all other machines is possible for this reason, because the entire arrangement is independent of the existing conditions at all times and remains rigid and immovable.

75 It will be noted that the diaphragm *i*₃ after the evacuation of the space below same may be lifted by the lever *h* which is fastened movably upon a shaft *n*', whereby the space may be still further evacuated.

80 The method of operation of the invention is as follows:

85 The radius of the hole to be burnt is set upon the scale *e*₁. Then the gear wheel *g* is oscillated, whereby the cutting burner is pushed away from the periphery of the hole to be cut for a distance corresponding to the oscillated segment toward the center of the hole. The centering arrangement *f* is folded downwardly in the position *f*' and set into the center punched hole *f*₁. Thereupon, the base plate *i* is set upon the article to be operated on and the operating shaft *l* turned to a certain extent. Thereby, the cams in the exemplary embodiment open the valve *k* and the valve *i*₄. Thereby the oxygen

passes under pressure from the valve k through on injector i_6 and a conduit o , still to be discussed, into the atmosphere. The oxygen through the conduit p and the likewise open valve i_4 and the conduit q moves

the air out of the plate i . A conduit i_2 which is connected with an evacuation meter r is thereby likewise evacuated. The degree of evacuation may be read off. By further turning of the shaft, the valves k and i_7 are closed. Then by means of lever m_1 , the diaphragm i_3 is lifted, whereby the interior of the plate i becomes still further evacuated and the entire arrangement is unfailingly held tight to the article being operated on. Upon further turning of the shaft, the gas valve i_7 and the oxygen valve k_3 are opened. Then the preheating jet is fed. Now the shaft is turned further, the cam lifts the valve k_3 and feeds the piercing burner b with oxygen, and the position for which it is set becomes pierced. Thereafter by actuation of the gear segment g , the ring burner b is pivoted away and stands over the pierced position of the hole to be cut, whereupon then the cut follows to the periphery by pivoting and thereupon the circular cut by turning the crank e .

When the hole is cut out, the shaft is again turned further, whereupon also the last valves become closed and thereby both burners b and c become free from oxygen and gas.

Upon a final rotation of the operating shaft, the valve i_4 is again lifted and thereby the interior of the plate i is put in communication with the outer air. Accordingly the device again becomes free from the article being operated on and may be set by means of the centering device f into the center punch hole of the next hole to be cut. Since the burners have now become warm through the previously cut hole, the oxygen used for the evacuation of the base plate may be connected through a conduit o which terminates in the vicinity of the burner and may cool the same advantageously during the setting time of the apparatus against the article being operated on.

The entire apparatus is provided with one or more handles which may be arranged as desired for convenient handling.

The mode of operation of the valves is briefly as follows. After the air has been sucked out of the suction plate i and the evacuation valve again closed, the piercing burner receives gas and oxygen for preheating and thereupon oxygen for piercing, while the two first valves close. After the shifting the ring burner receives heating gas and heating oxygen and thereupon simultaneously cutting oxygen. After the completion of the cut, all the valves are closed, only the evacuation valve is again opened and the plate freed. The piercing burner is pro-

vided with only one jet and discharges, on the one hand, a gas-poor mixture for rapid preheating, and on the other hand, directly the oxygen for the piercing.

What is claimed to be new is:

1. An apparatus of the class described comprising a base, a centering implement for cooperating with the work to determine the position of the base, burners, valves for controlling the supply of gas to the burners, and means to insure the flow of gas acting as a suction medium on the interior of the base to hold the base fixed with respect to the surface on which it is operating.

2. An apparatus of the class described, comprising a hollow base, a sealing edge therefor, burners, valves for controlling the admission of gas to the burners, manually operable means for successively operating the valves, and a valve for controlling the passage of gas for exhausting the air from the interior of the base.

3. An apparatus of the class described, comprising a hollow base, a sealing edge therefor, burners, valves for controlling the admission of gas to the burners, manually operable means for successively operating the valves, a valve for controlling the passage of gas for exhausting the air from the interior of the base, and manually operable means within the base for increasing the interior area of the base following the suction effect, whereby to increase the holding power of the base.

4. An apparatus of the class described including a hollow base having a sealing edge, burner jets carried by and movable with respect to the base, valves on said base for controlling the feeding of gas to the jets, an injector having communication with the interior of the base, an additional valve on the base, and a connection between said additional valve and the injector to utilize the passage of gas through said valve as a means of exhausting the interior of the base.

5. An apparatus of the class described including a hollow base having a sealing edge, burner jets carried by and movable with respect to the base, valves on said base for controlling the feeding of gas to the jets, an injector having communication with the interior of the base, an additional valve on the base, a connection between said additional valve and the injector to utilize the passage of gas through said valve as a means of exhausting the interior of the base, a diaphragm arranged within the hollow base, and means for manually operating the diaphragm to increase the area within the base open to the suction effect.

6. In an apparatus of the class described, a base, burner jets movable with respect to the base, valves for controlling the passage of gas to said jets, said valves being arranged in spaced parallel series, and a manu-

ally operable element arranged intermediate the valves and adapted in operation to successively control the valves.

7. In an apparatus of the class described, 5 a base, burner jets movable with respect to the base, valves for controlling the passage of gas to said jets, said valves being arranged in spaced parallel series, a manually operable element arranged between the 10 valves, cams on said element, and means whereby each cam is adapted in a predetermined position of the element to control one of the valves.

8. An apparatus of the class described 15 comprising a preheating burner, a cutting burner, a pantograph support for both burners, a pivot about which the pantograph support is movable, a support for the pivot, a bar connected to the pivot of the pantograph, a sector-shaped plate connected to the support and over which the bar is movable, and means carried by the bar and co-operating with the plate to provide for holding the bar in adjusted position with respect 25 to the plate against casual displacement.

9. An apparatus of the class described including a preheating burner, a cutting burner, a pantograph support for both burners, a pivot about which the pantograph support is movable, a support for the pivot, a bar connected to the pivot for the pantograph, a sector-shaped plate connected to the support and over which the bar is movable, and a gear carried by the bar to 30 cooperate with teeth formed on the curved edge of the sector plate to thereby hold the bar against casual displacement in any adjusted position relative to the plate.

10. An apparatus of the class described 40 including a preheating burner, a cutting burner, a pantograph support for both burners, a pivot about which the pantograph support is movable, a support for the pivot, a bar connected to the pivot for the pantograph, a sector-shaped plate connected to the support and over which the bar is movable, a gear carried by the bar to cooperate with teeth formed on the curved edge of the sector plate to thereby hold the bar 45 against casual displacement in any adjusted position relative to the plate, a bolt carried by the pantograph for operation thereof, a graduated rod slidably connected to said bolt, and a connection between one end of said rod and said bar, said connection providing a center about which the bolt moves 50 as a crank in governing the movement of the burners.

In testimony whereof I affix my signature.
60 HANS GREGGERSEN. [L. s.]
